UNITED STATES PATENT OFFICE.

ELMER L. RUSSELL, OF GREAT FALLS, MONTANA.

AEROPLANE.

1,238,572.

Specification of Letters Patent. Patented Aug. 28, 1917.

Application filed September 27, 1916. Serial No. 122,473.

To all whom it may concern:

Be it known that I, ELMER L. RUSSELL, a citizen of the United States, and a resident of Great Falls, in the county of Cascade and State of Montana, have invented a certain new and useful Improvement in Aeroplanes, of which the following is a specification.

My present invention relates generally to aeroplanes, and more particularly to an aeroplane of the type to be hereinafter described, the object and advantages of which will be clearly outlined in the following description thereof.

15 To this end reference is made to the accompanying drawings, forming part of this specification, and wherein—

Figure 1 is a plan view illustrating my improvements.

20 Fig. 2 is a transverse section through one side extension of the upper plane, taken on line 2—2 of Fig. 1.

Fig. 3 is a side elevation.

25 Fig. 4 is a detail perspective view of the upper planes, illustrating in more or less diagrammatic manner the controlling connections for the ailerons carried thereby.

Fig. 5 is a front elevation, and

30 Fig. 6 is a detail view more or less diagrammatic illustrating the vertical tail plane and the control therefor.

Referring now to these figures, it is preferable for certain reasons presently to be referred to that the aeroplane be of the tri-plane type, the planes 10, 11, and 12 being constructed in superposed relation within a frame including vertical struts 13 of which those at the sides of the plane are extended above the upper planes 12 as best seen in Figs. 3, 4, and 5, and as indicated at 40 14 in these figures.

The upper plane 12 is also provided with lateral extensions 15 which combined approximate in area the area of one of the main planes, it being noted that these extensions 15 are inclined outwardly and upwardly and that this inclination is their normal position, guy wires 16 and 17 rigidly holding the same in position. The guy wires 16 lead to the lower side portions of the main frame, while the guy wires 17 lead upwardly to the extensions 14 of the side struts of the main frame, as before described.

45 50 The fuselage 18 is centrally located between the lower plane 10 and the intermediate plane 11 and carries a motor bed 19 and motor 20 at its forward end forwardly of the main planes and below the center of gravity of the machine as thus far described, 55 the rearwardly extending motor shaft 21 being connected by sprocket wheels and a sprocket chain 22, the latter of which extends through tubular casings 24, to the upper propeller shaft 25 mounted between 60 the intermediate plane 11 and the upper plane 12, and having a propeller 26 secured upon its forward end forwardly of the several main planes.

It will be noted by reference to Figs. 3 70 and 5 in particular that the main frame and the fuselage 18 conjointly support the forward landing wheels 27 and that the rear end of the fuselage 18, as particularly seen in Fig. 3, is provided with landing skids 28. 75

The rear end of the fuselage 18 is also provided with a vertical rudder 29 and with horizontal rudders or elevators 30 upon opposite sides of the vertical rudder 29. The controlling cables of the horizontal rudders 80 or elevators 30 are shown at 31 and the controlling cables of the vertical rudder 29 are shown at 32, being particularly seen in Fig. 6. The particular controls for actuating these tail rudders in operation are relatively unimportant, various well known means being utilized for this purpose, such as, for instance, a steering wheel 33, as seen in several of the figures, particularly Fig. 6, and disposed at the operator's station, in the 85 forward portion of the fuselage 18, rearwardly of the motor bed 19, the operator's seat being seen at 34 in Fig. 3.

Thus, due to the upward inclination of the lateral extensions of the upper frame, 90 the machine when thrown out of balance in use, makes a side slip and rights itself automatically, making it practically impossible for it to tip over sidewise. In order to hold the machine straight in landing, however, I 100 preferably provide the rear edges of the extensions 15 of the upper plane 12, with rearwardly projecting hinged ailerons 35 and 36, connected across the top of the plane 12 and its said extensions by a connecting cable 105 37 extending around pulleys 38 as best seen in Fig. 1, so as to constrain the two ailerons to movements in relatively opposite directions, the control for the movements of the ailerons being in the form of an intermediate pivoted foot bar 39 from which cables 110 40 and 41 respectively lead to the under side

of the ailerons 35 and 36, the foot bar being arranged in front of the operator's seat as shown in Fig. 3.

It is to be observed, furthermore, that the motor being in the position described, carried between the lower and intermediate planes, and being thus below the center of pressure, makes it impossible for the machine to dive straight to the ground or fall backward, and for the purpose of this feature it is, of course, preferable that the machine be of the triplane type as first above noted, that is, that the machine include at least three planes in superposed relation. For the purpose of the automatically balancing inclined extensions of the upper plane, however, the machine may be of the biplane type, attention being called again to the fact that the ailerons are not necessary to balance the machine when in flight,

but are used more particularly for landing purposes.

I claim:—

An aeroplane having superposed planes of which the upper plane is provided with rigid upwardly inclined extensions projecting beyond the ends of the lower planes, ailerons hinged to the rear edges of the said upwardly inclined extensions, a cable connecting the upper surfaces of the said ailerons and extending across the top of the upper plane, an intermediately pivoted foot-control bar, and cables extending from the opposite ends of said control bar to the lower surfaces of the said ailerons for the purpose described.

ELMER L. RUSSELL.
